RECEPTACLE COVER

Robert H. Jamison, Cleveland Heights, Ohio, assignor to The Stay-On Manufacturing Company, Cleveland, Ohio, a corporation of Ohio

Application November 9, 1932, Serial No. 641,839

8 Claims. (Cl. 220—56)

This invention relates as indicated to receptacle covers and more particularly to covers such as are commonly employed on garbage cans and the like, the conditions of use of which require that some means be provided for quickly and effectively locking the cover onto the container against displacement occasioned by animals and the like.

It is among the objects of my invention to provide a cover for receptacles which is provided with a manipulating handle so formed and related to the remaining structure that the normal movement of the handle to take off the cover automatically renders the locking device inoperative and when the cover is replaced on the receptacle, the locking device becomes effective without any further act on the part of the user.

Other objects of my invention will appear as the description proceeds.

To the accomplishment of the foregoing and related ends, said invention, then consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:—

30 Fig. 1 is a side elevational view of a receptacle provided with a cover constructed in accordance with the principles of my invention; Fig. 2 is a fragmentary side elevational view of the structure illustrated in Fig. 1; Fig. 3 is a fragmentary transverse sectional view drawn to an enlarged scale of the structure illustrated in Figure 2, taken on a plane substantially indicated by the line 3—3; Fig. 4 is a fragmentary perspective view of the locking handle mounted on the cover; Fig. 5 is a fragmentary perspective view of the handle receiving slot and its associated projection formed in the margin of the cover; Fig. 6 is a fragmentary perspective view of the latch provided on the cover at a point diametrically opposite to the point occupied by the slot illustrated in Figure 5; Fig. 7 is a fragmentary perspective view of the lower latching end of the handle; and Fig. 8 is a fragmentary, part sectional, part elevational view showing the manner in which the handle is secured at its upper end to the cover.

Referring now more specifically to the drawing and more especially to Figures 1 to 3, the cover comprising my invention is adapted to be employed in conjunction with any common form of

receptacle, generally indicated at 1, such as a garbage can, refuse container and the like.

As is usual in the construction of cans or containers of this character, the side wall 1 of the container adjacent its open end is provided with an outwardly extending reinforcing bead 2 which, not only reinforces and strengthens the upper open end of the wall of the can, but also serves as a means to be engaged by the locking devices associated with the cover comprising my invention. It is to be noted that the can and its associated cover are illustrated in the drawing as being round, although it is to be understood that the cross-section of such can and cover may vary from this form without departing from the principles of my invention. The cover 3 for the can is given a suitable contour by stamping or otherwise so as to be properly reinforced and is also provided with a depending axially extending flange 4 adapted to extend downwardly over the bead 2 on the can. The inner periphery of the flange 4 is such that the cover will easily slide over the bead 2. Sufficient clearance should be provided so that the cover may be put on and taken off easily without binding and yet not too much clearance so that the latching handle presently to be described may not function.

As above indicated, my invention relates particularly to the provision of a handle generally indicated at 5, which, at its upper end, is provided with a suitable aperture through which extends a securing rivet 6 loosely attaching the upper end of the handle to the cover. The shank 7 of the rivet 6 is preferably somewhat smaller than the aperture 8 provided therefor in the handle 5, so that some movement may occur between the handle and cover at its upper end. The head 9 of the rivet is formed sufficiently large so that the handle may not be pulled off from the supporting rivet 6.

At a point on the flange 4, preferably on the same radial line with the rivet 6 is provided an axially extending slot generally indicated at 10 through which the lower end 11 of the handle 5 extends. This lower end 11 of the handle is provided with laterally projecting ears 12 which engage the inner surface of the flange 4 so that the handle is secured against displacement in the slot 10.

At the upper end of the slot 10 in the flange 4 are provided struck-out portions 13 of such shape and proportion as to accommodate the projections 11 when the handle is moved to the dotted line position as illustrated in Figure 3.

At a point on the flange 4 diametrically opposite from the slot 5, some means such as struck-

out portions 14 must be provided to project inwardly for a distance sufficient to engage the under side of the bead 2 and prevent dislodgment of the cover on this side of the can.

5. The operation of the above described latching device may be briefly described as follows:—

Assuming that the cover 3 is in position on the can 1, the handle 5 will then normally rest in the full line position as illustrated in Fig. 3. Any attempt to remove the cover from the can will be opposed by the projections 12 engaging the under side of the bead 2, unless the handle is first moved into dotted line position, as illustrated in Fig. 3, so that such projections lie within the space provided therefor by the struck-out portions 13. When the handle is moved to the dotted line position and such movement occurs as a normal result of a lift thereon preliminary to lifting the lid, the bead will slide down over the inner periphery of the flange 4 without any obstruction in the vicinity of the latch. Even though the body of the can should become deformed, i. e., pressed out of true circular shape so as to cause the bead 2 to rest tightly against the inner periphery of the flange 4 in the vicinity of the handle, the raising of the handle to the dotted line position moves the projections 12 on the inner end of the handle entirely clear of such bead so that there is no interference in removing the cover.

30. Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. The combination with a receptacle having an external bead around the wall thereof adjacent its open end, of a cover for said receptacle having a depending flange extending downwardly over said bead, a manipulating and locking handle secured at its upper end to said cover in a hinged relation and its lower end extending through an axially extending slot in said flange, a projection on the lower end of said handle securing the same in said slot and practically spanning the space between said flange and the wall of said receptacle, and a portion of said flange adjacent the upper end of said slot struck out to accommodate said projection, when said handle is in an unlocked position, the axial edges of said slot comprising lines having depressions therein formed by said struck out portions, the remainders of said lines lying in the general plane of said flange.

2. The combination with a receptacle having an external bead around the wall thereof adjacent its open end, of a cover for said receptacle having a cylindrical flange of an inside diameter slightly greater than the outside diameter of said beaded portion, a manipulating and locking handle secured at its upper end to said cover in hinged relation and its lower end extending through an axially extending slot in said flange, a projection on the lower end of said handle securing the same in said slot, said projection having a thickness slightly less than the radial space between said receptacle and cover, and a portion of said flange adjacent the upper end of said slot struck out to accommodate said projection, the axial edges of said slot comprising lines having depressions therein formed by said struck out portions, the remainders of said lines lying in the general plane of said flange.

3. The combination with a receptacle having an external bead around the wall thereof adjacent its open end, of a cover for said receptacle having a depending flange adapted to extend for at least a short distance below said bead, an axially extending slot in said flange extending below said bead when said cover rests on said receptacle, a manipulating and locking handle secured at its upper end to said cover in a hinged relation and at its lower end extending through said slot, a projection on the lower end of said handle securing the same in said slot, said projection having a thickness slightly less than the radial space between said receptacle and cover, and a portion of said flange adjacent the upper end of said slot struck out to accommodate said projection, the axial edges of said slot comprising lines having depressions therein formed by said struck out portions, the remainders of said lines lying in the general plane of said flange.

4. The combination with a receptacle having an external bead around the wall thereof adjacent its open end, of a cover for said receptacle having a depending flange adapted to extend for at least a short distance below said bead, an axially extending slot in said flange extending below said bead when said cover rests on said receptacle, a manipulating and locking handle secured at its upper end to said cover in a hinged relation and at its lower end extending through said slot, a projection on the lower end of said handle securing the same in said slot, said projection having a thickness slightly less than the radial space between said receptacle and cover, a portion of said flange adjacent the upper end of said slot struck out to accommodate said projection, the axial edges of said slot comprising lines having depressions therein formed by said struck out portions, the remainders of said lines lying in the general plane of said flange.

5. The combination with a receptacle having an external bead around the wall thereof adjacent its open end, of a cover for said receptacle having a depending flange adapted to extend at least a short distance below said bead, said flange having an axial slot therein, and opposite said slot a projection adapted on lifting the cover vertically to engage the under side of said bead, a handle mounted on the top of said cover in hinged relation therewith, said handle having a downwardly turned hook-shaped section which passes through said slot and terminates in a portion wider than said slot, said terminal portion being adapted to loosely span the space between said flange and said receptacle, and on the inside of said flange near the top of said slot a struck out section forming a recess adapted to receive said wider portion when the cover is in unlatched position, said recess when the receptacle is closed being just below said bead, the axial edges of said slot comprising lines having depressions therein formed by said struck out portions, the remainders of said lines lying in the general plane of said flange.

6. The combination with a receptacle having an external circumferential bead on the wall thereof adjacent its open end, of a cover for said receptacle having a depending flange with an axially extending slot therein which extends below said bead when said cover seats on said receptacle, a handle for said cover secured thereto at its upper end in hinged relation and at its lower end ex-

- tending through said slot, a terminal element on the lower end of said handle of slightly less thickness radially of the receptacle than the space between said flange and said bead, means adapted to retain said lower end of said handle in said slot, and a portion of said flange, adjacent the upper end of said slot and just below said bead when the cover is seated, struck out to form a recess adapted to accommodate said terminal element when the said handle is lifted, the axial edges of said slot comprising lines having depressions therein formed by said struck out portions, the remainders of said lines lying in the general plane of said flange. 80
- 10 7. The combination with a receptacle having an external projection around the wall thereof adjacent its open end, of a cover for said receptacle, a depending flange on said cover adapted to extend below said projection when said cover is seated, and having an axial slot therein, means inside said depending flange adapted to engage said projection when said cover is lifted, a handle mounted by one end on the top of said cover in hinged relation therewith, said handle having a 90 downwardly turned end passing through said slot and terminating in a portion adapted to retain said end within said slot and to loosely close the gap between said flange and the wall of said receptacle when the cover is in position thereon, and a struck out section on the inside of said depending flange, adjacent the upper end of said slot and communicating therewith, forming a 95 recess adapted to receive said terminal portion when said handle is lifted to unlatch and raise the cover, said recess being located just below said external projection of the receptacle when said cover is in place thereon, the axial edges of said slot comprising lines having depressions therein formed by said struck out portions, the remainders of said lines lying in the general plane of said flange. 100
- 15 8. In a cover for a receptacle having a circumferential projection about the external wall near the top thereof, a downwardly turned flange adapted to freely but closely encompass said projection, which flange has an axial slot therein, a handle hingedly mounted on the top of said cover which handle has a downwardly turned portion passing through, and slidably secured in said slot, an element on the end of said handle of slightly less thickness radially of the receptacle than the space between the said flange and said projection, and near the top of said slot and in communication therewith a struck out portion of said flange forming a recess adapted to accommodate said element when the said handle is lifted, said recess being so located that it is 105 blocked by said projection when the said cover is moved slightly off its seat on said receptacle, the axial edges of said slot comprising lines having depressions therein formed by said struck out portions, the remainders of said lines lying in the general plane of said flange. 110
